UNITED STATES PATENT OFFICE.

VIRGIL ARIEL STEVENS, OF GREEN COVE SPRINGS, FLORIDA.

GARMENT PRESSER AND CREAMER.

Application filed September 30, 1926. Serial No. 138,793.

The present invention relates to devices primarily intended for use in placing creases in trousers, or other garments, and which devices may also be employed for use 5 in pressing the wrinkles from flat pieces of cloth materials such as shirts, neckties and the like.

The primary object of the invention is to provide a combined garment presser and 10 creaser which is of extremely light construction thus rendering the same portable for use by persons when traveling, and which device may be operated for placing creases in trouser legs without necessarily removing 15 the trousers.

A further object of the invention is to provide an electrically heated garment presser embodying a moistening means whereby the 20 material being creased will not become shiny during the creasing operation.

A still further object of the invention is to provide an improved garment creaser embodying a pair of heated creasing rollers with moistening rollers for each creasing 25 roller, and which rollers are adapted to support moistening belts which are brought into contact with the garment between the creasing rollers in a manner for preventing possible scorching of the garment and also 30 preventing any possible rolling contact of the creasing rollers with the garment.

A still further object of the invention resides in the provision of a device of this character which is extremely simple and 35 durable in construction, and which may be effectively used for placing creases in trouser legs without the requiring of any great amount of skill.

Other objects and advantages of the invention will be apparent during the course 40 of the following detailed description, taken in connection with the accompanying drawing forming a part of this specification and in which drawing:

45 Figure 1 is a view part in side elevation and part in section, and showing the improved device in position for applying of a crease to a garment.

Figure 2 is a top plan view of the device.

50 Figure 3 is a sectional view through one of the creasing rollers and taken on line 3—3 of Figure 1.

55 Figure 4 is a sectional view through one of the combined moistening and tensioning rollers and taken on line 4—4 of Figure 1.

In the drawing, similar reference characters designate corresponding parts throughout the several views.

Referring to the drawing in detail, the device embodies a pair of arms 5 and 6 preferably formed of relatively thin strips of metal, and which arms are pivotally connected at their intermediate portions by means of a suitable pivot pin 7. Formed integral with the rear end of the arm 5, is an offset handle 8 provided with a thumb grip 9, and formed integral with the rear end of the arm 6, is a handle portion 10 provided with a finger grip 11 which coacts with the thumb grip 9 in a manner whereby upon spreading 65 of the grip portions 9 and 11, the forward free end of the arms 5 and 6 will also be moved away from one another.

Mounted upon the forward end of each of the arms 5 and 6, are creasing rollers 12 and 13 respectively. These rollers 12 and 13 are of identical construction and each embodies a mounting shaft 14 adapted to be mounted in right angular relation upon its respective mounting arm. Each of the 75 mounting shafts 14 embodies a cylindrical body portion 15 having a reduced screw threaded shank portion 16 provided at its inner end for passing through an aperture 17 provided adjacent the forward end of its 80 mounting arm.

Each of the creasing rollers 12 and 13 embodies a metallic tubular drum 18 having a rabbet or annular recess 19 provided on its inner surface at each end of the drum. Closing the inner end of the drum 18, is a disc like head 20 provided with an axially disposed hub portion 21 which is adapted to seat upon the shoulder formed by the reduced shank portion 16. Closing the outer 95 end of the drum 18, and seating in the annular recess at the outer end of the drum, is an outer closure head 22 provided with a hub 23 for bearing engagement with a shoulder provided adjacent the outer end of the cylindrical body portion 15. The outer end of the body portion 15 is spread over the outer face of the head 22 as at 24 for rigidly mounting the head against rotation on the shaft. Threaded upon the shank portion 16 105 at the outer face of the head 20, is a binding nut 25 which when turned into engagement with the outer face of the head, securely retains the head 20 against rotation on its mounting shaft. Thus it will be seen that 110

the heads 20 and 22 are rigidly mounted upon their respective shafts 14, and that the tubular drums 18 revolve about the heads.

Clamping nuts 26 are threaded upon the shank portions 16 for rigid mounting of the creasing rollers upon their respective arms 5 and 6, with the mounting shafts 14 of the rollers extending in parallel relation to one another.

10 Mounted within each of the creasing rollers 12 and 13, is a heating unit 30 embodying a cylindrical mounting core 31 formed of a suitable insulating material, and which core is suitably fixed upon the body portion 15 of the shaft 14 with its ends spaced from the heads 20 and 22. These cores 31 are of less diameter than the internal diameter of the drums 18, and are adapted to support spirally wound resistance wires 32 having 15 their leads 33 extending through insulating bushings carried by the fixed inner head 20. These leads 33 may be connected to a suitable extension wire provided with a plug for inserting in an electric lamp socket or 20 other suitable electrical outlets. Upon passing a current through the wire 32, the same will become heated for heating of the tubular metallic drums 18.

Mounted at the rear end of each of the 30 arms 5 and 6, is a moistening roller 35 embodying a mounting shaft 36 for nonrotatable mounting of inner and outer disc like heads 37 and 38 respectively. The inner end of the shaft 36 is provided with a reduced screw threaded shank portion 39 for receiving a binding nut 40 which serves for forcing the inner head 37 into tight engagement with a shoulder formed at the junction of the reduced threaded shank portion 39 with the body portion of the shaft. The reduced portion 39 is adapted to extend through the inner ends of the arms and receive a clamping nut 41 for rigidly mounting 45 of the shafts 36 in parallel relation to one another and with the axis of the shafts 14 carried by the forward end of the arms 5 and 6. The outer end of each shaft 36 is provided with a reduced threaded portion 42 for receiving a nut 43 whereby the outer 50 head 38 is removably mounted upon the outer end of the shaft.

Mounted for rotation about the heads 37 and 38, is a tubular drum 44 provided with a suitable number of perforations 45, the drum also being provided at its ends with inwardly formed annular recesses 46 which form bearings for the drum, and which also prevent longitudinal movement of the drum off of the supporting heads 37 and 38.

60 These perforated drums 44 are adapted to receive a suitable absorbent material such as a sponge or a wad of raw cotton 48, the absorbent material being readily removable from the drum upon removing the nut 43 and outer head 38. It is preferred that

this absorbent material 48 remain stationary within the moistening drum, so that upon rotation of the drum 44, the apertures 45 due to their sliding movement over the absorbent material, will take up a sufficient amount of liquid from the material and direct the liquid to the outer surface of the drum. The absorbent material 48 is preferably soaked with water before being positioned within the moistening roller.

75 By observing Figure 1, it will be seen that the moistening rollers 35 are of less external diameter than that of the heated creasing rollers 12 and 13, and the object of which will be subsequently brought out.

80 Trained over each of the creasing rollers 12 and 13, and over their companion moistening rollers 35, is an endless cloth belt 50 of a width equal to the length of the rollers. These cloth belts 50 serve as protecting belts for protecting the trouser leg or other garment from being scorched, since the belts become thoroughly moistened during their rolling movement over the moistening rollers 35. These moistening belts 50 upon 85 coming in contact with the heated creasing rollers 12 and 13, will create a slight amount of steam for providing a sharp and pronounced crease in the material being operated upon. By so having the belts 50 of a width equal to the length of the creasing rollers 12 and 13, and the moistening rollers 35, will prevent possibility of the metallic drums of the creasing rollers from contacting with the material being creased.

90 It may here be well to state that in the use of the device for forming a crease in a trouser leg, the device is first moved in a direction as indicated by the arrow in Fig. 1, and which general movement of the device will cause the coating belt 50 to travel in a direction as indicated by the arrows.

95 Rigidly carried by the outer end of each of the creasing rollers 12 and 13, and also the moistening rollers 35, is a V-shaped 100 guide 55 the arms of which project inwardly for a slight distance in overlying spaced relation to the circumferential face of the rollers. These guides 55 serve for retaining the belt 50 in position upon the rollers when 110 the device is in its spread position, and in which spread position the belts become loose upon their rollers due to the fact that the rollers are brought closer together when the device is in its spread position. The arms 115 5 and 6 will prevent the belt from sliding off of the inner sides of the rollers.

120 A suitable spring 60 is disposed between the arms 5 and 6 forwardly of their pivotal connection 7, for normally urging the rollers 12 and 13, and the rollers 35 away from one another.

125 When the device is in its closed operative position, it is preferred that the creasing rollers 12 and 13 engage one another slightly 130

in advance of contacting of the grip portions 9 and 11, and which contacting of the opposite ends of the device will at all times retain the moistening rollers 35 in spaced apart relation.

In operation of the device, and with the arms 5 and 6 in their normal spread position by reason of the spring 60, the leads 33 of the heating units 30, are connected with a suitable supply of electric current, for heating of the metallic drums 18. The operator then grasps the grips 9 and 11 and positions the device over the material with the fold of the material extending longitudinally of the device between the creasing rollers 12 and 13 and also between the moistening rollers 35. The grips 9 and 11 may then be brought together in a similar manner to the closing of shears, and which operation will tighten each of the moistening belts 50 and also move the belts into engagement with opposite sides of the material at a point between the creasing rollers 12 and 13. With the rollers 12 and 13 so clamped about the material, the device is moved back and forth along the material until the crease is perfectly formed at the fold of the material. During this back and forward movement of the device, the belts 50 are moistened by means of their respective moistening rollers 35, and these moistened belts are moved between the creasing rollers and the material for suitably dampening the material and producing a sharp crease therein. It will be noted that when the device is moved along the material being creased, that no sliding movement of the belt over the material occurs, and thus eliminates any likelihood of the material becoming shiny during the creasing operation.

By having the moistening rollers 35 spaced from the material during the creasing operation, the moistened belts 50 will not contact with the material for further dampening the material after passage of the creasing rollers thereover. This would be apt to occur when the device is moved in a direction counter to that direction as indicated by the arrow in Figure 1.

When the device is used as a roller presser for pressing articles such as shirts, collars, ties and the like, merely one of the heated rollers and its companion moistening roller is employed, the device merely being rolled along the articles to be pressed. By observing Figure 1 it will be seen that either companion set of rollers may be used for pressing flat articles, since the guides 55 and supporting arms for the rollers are disposed inwardly of the upper and lower edges of the device.

From the foregoing description it will be apparent that an improved and novel type of combined garment presser and creaser has been provided, embodying novel features of

construction whereby a material being operated upon is automatically dampened by the device, and which device embodies an arrangement of parts whereby no sliding movement of the device along the material is had during operation of the device. It will also be apparent that a device of this character has been provided which is of extremely simple and durable construction, and which is susceptible of being carried by persons when travelling, for the performing of certain pressing operations without necessarily sending the garments out to be pressed.

Various changes may be made to the specific form of the invention herein shown and described, without departing from the spirit of the invention or the scope of the following claims.

I claim:

1. In a device of the class described, the combination of a pair of arms pivotally connected intermediate their ends, pressing rollers rotatably carried by the forward end of each arm, tensioning rollers rotatably carried by the rear end of each arm and extending parallel with the pressing rollers, endless belts trained over each pressing roller and the tensioning roller carried by the opposite arm from which the pressing roller is mounted, and means for moving the belts, together with their supporting rollers, laterally toward and away from one another.

2. In a device of the class described, the combination of a pair of arms pivotally connected intermediate their ends, creasing rollers rotatably carried by the forward end of each arm, tensioning rollers of less diameter than said creasing rollers, carried by the rear end of each arm and extending parallel with the creasing rollers, endless belts trained over each creasing roller and the tensioning roller carried by the opposite arm from which the creasing roller is mounted, and means for moving the belts, together with their supporting rollers, laterally toward and away from one another, comprising handle portions carried by the rear end of each arm and provided with grip portions, said creasing rollers and grip portions contacting when the device is in its closed position for retaining the tensioning rollers in spaced apart relation.

3. In a device of the class described, the combination of a pair of arms pivotally connected intermediate their ends, creasing rollers rotatably carried by the forward end of each arm, heating means for said rollers, tensioning rollers rotatably carried by the rear end of each arm and extending parallel with the creasing rollers, moistening means carried by said tensioning rollers, endless belts trained over each creasing roller and the tensioning roller carried by the opposite arm from which the pressing roller is mount-

ed, said belts being moistened in their movement about the tensioning rollers, and means for moving the rollers toward and away from one another.

- 5 4. In a device of the class described, the combination of a pair of arms pivotally connected intermediate their ends, creasing rollers rotatably carried by the forward end of each arm, heating units mounted in each 10 creasing roller, moistening rollers rotatably carried by the rear end of each arm and extending parallel with the creasing rollers, endless belts trained over each creasing roller and the moistening roller carried by the opposite arm from which the creasing roller is mounted, said belts to be moistened by movement about the moistening rollers, and means for moving the creasing and the moistening rollers toward and away from one another.
- 15 5. In a device of the class described, the combination of a pair of arms pivotally connected intermediate their ends, creasing rollers rotatably carried by the forward end of each arm, heating units mounted in each of 20 said rollers, perforated moistening rollers rotatably carried by the rear end of each arm and extending parallel with the creasing rollers, moistening material disposed in each of said moistening rollers, endless belts 25 trained over each creasing roller and the moistening roller carried by the opposite arm from which the creasing roller is mounted, and means for moving the creasing rollers and the moistening rollers toward and away from one another with the belts 30 at the creasing rollers movable into engagement with one another.
- 35 6. In a garment creaser, the combination of a pair of arms pivotally connected intermediate their ends, shafts rigidly carried by the forward end of each arm and extending in parallel relation to one another, spaced 40 heads rigidly mounted on each shaft, heating units mounted on each shaft between said heads, tubular drums rotatably mounted on said heads, and encircling said heating units, moistening rollers rotatably carried 45

50 by the rear end of each arm and having their axes extending parallel with the axes of said shafts, endless belts trained over each tubular drum and the moistening roller carried by the opposite arm from which the tubular drum is mounted, and means for moving the tubular drums and the moistening rollers toward and away from one another.

55 7. In a device of the class described, the combination of a pair of arms pivotally connected intermediate their ends, creasing drums rotatably carried by the forward end of each arm, means for heating said drums, 60 moistening drums rotatably carried by the rear end of each arm and extending parallel with the creasing drums, endless cloth belts trained over each creasing drum and the moistening drum carried by the opposite arm 65 from which the creasing drum is mounted, guides mounted at the outer end of each drum for preventing movement of the belt off the drums, and means for moving the creasing drums and the moistening drums 70 toward and away from one another.

75 8. In a garment creaser, the combination with a pair of arms pivotally connected intermediate their ends, and rotatable creasing members carried by the forward end of each arm and each provided with a heating element, of moistening means for the creasers comprising perforated moistening drums 80 rotatably carried by the rear end of each arm and extending parallel with the creasing members, a packing of absorbent material removably disposed in each of said perforated moistening drums, endless belts trained over each creasing member and the moistening drum carried by the opposite 85 arm from which the creasing member is mounted, and means for moving the creasing members and the moistening drums toward and away from one another, said means serving to prevent contacting of the 90 moistening drums when those portions of the endless belts are moved into contacting engagement between the creasing members.

VIRGIL ARIEL STEVENS.
